UNITED STATES PATENT OFFICE.

FREDERICK P. UPHAM, GEORGE A. SAUNDERS, AND HENRY A. SHELDON, OF PAWTUCKET, ASSIGNEES OF ONE-HALF TO JOHN E. GOLDSWORTHY, OF CENTRAL FALLS, RHODE ISLAND.

CLOTH-STRETCHING MACHINE.

SPECIFICATION forming part of Letters Patent No. 258,947, dated June 6, 1882.

Application filed January 6, 1879.

To all whom it may concern:

Be it known that we, FREDERICK P. UPHAM, GEORGE A. SAUNDERS, and HENRY A. SHELDON, all of the town of Pawtucket, county of Providence, and State of Rhode Island, have invented new and useful Improvements in Cloth-Stretching Machines; and we do hereby declare that the following, taken in connection with the drawings which accompany and form part of this specification, is a description of our invention sufficient to enable those skilled in the art to practice it.

Our invention relates to cylindrical cloth-stretching machines which increase the width of the cloth as it passes over the surface of a revolving cylinder, with which the machine is provided.

The invention consists mainly in the novel combination of the cam-disk and guide-wheel used to operate the stretcher-blocks and the jointed arm employed to hold them in proper position, in the mechanism for regulating the stretch while the machine is at rest or in operation, and in the combination for oiling the cam-disks and guide-wheels.

In the drawings, Figure 1 represents a plan of our machine, partly in section. Fig. 2 is an elevation of the cylinder-head, showing also the adjustable bar over which the cloth passes, the stanchion, and the devices for adjusting the said bar. Fig. 3 is a plan of the jointed arm that connects the cam-disk and the disk in the cylinder-head. Fig. 4 is an elevation of the jointed arm. Fig. 5 represents the jointed arm attached to the central shaft instead of to the cylinder-disk. Fig. 6 is a front elevation of the cam-disk and guide-wheel, with portions of the same broken away to show the reservoir in the cam-disk and the perforations through which the oil is supplied to the bearings of the said disk and guide-wheel. Fig. 7 is a vertical section of the guide-wheel and cam-disk, also showing the lug connecting the guide-wheel and stretcher-blocks and the manner of linking the latter together. Fig. 8 is a top view of one of the stretcher-blocks. Fig. 9 is an end view of the machine, showing the hand-wheel, gear, and worm-gear for operating the adjusting-rod.

The surface of the cylinder with which the machine is provided is made up of a number of parallel rows of stretcher-blocks, which have serrated surfaces for gripping the cloth while in contact with the cylinders. These blocks are linked together, and move simultaneously in two longitudinal series from the center of the row toward each end of the cylinder during the stretching process, then backward to the center as they successively leave the cloth. Thus during one-half the revolution of the cylinder each row of stretcher-blocks performs a stretching service, and successively repeats this service in every revolution. The devices employed to operate the several rows of stretcher-blocks are chambered guide-wheels, each of which is secured to and rotates on a cam-disk that is fitted to the chamber in the guide-wheel and secured to the central shaft of the machine.

Referring to the drawings, the central shaft, A, is supported at each end by stanchion or otherwise, and is stationary. Attached to the central shaft at each end of the machine between the points of support are disks K, Fig. 1, which are incased by the cap f inside and the cylinder-head H outside. Also attached to the central shaft within the cylinder are the devices for actuating the stretcher-blocks C, set opposite each other near the ends of the cylinder. They occupy converging planes, which intersect diagonally the longitudinal axis of the central shaft. These actuating devices are each composed of two parts—the stationary cam-disk B', which is secured to hubs v, Fig. 7, opposite each other on the sleeve F of the shaft A, and the guide-wheel B, which rotates around the cam-disk B' and governs the movement of the stretcher-blocks C. The periphery of the guide-wheels is furrowed out to receive the lug x, secured to the end block of each row of stretcher-blocks. The guide-wheels are made in two sections, and are hollow to receive the cam-disk, and when fastened together completely incase the same. The cam-disk is chambered out to serve as a reservoir for oil or other lubricant used about it and the guide-wheel. Perforations q, Fig. 6, through the shell of said disk, supply the oil in sufficient

quantities from the reservoir R. The pipe p, Fig. 7, serves to conduct the oil into the reservoir. By these contrivances the oil is all utilized, none escapes to injure the fabric that passes over the cylinder, and the frequent oiling of these parts is thereby avoided. Ears e, Fig. 7, project from each of the cam-disks, and are employed to secure the said disks to the sleeves F, the said sleeves at the point of contact being provided with hubs v, to which the ears e are secured by bolts or screws s, with sufficient intervening space to allow a little freedom on the bolts or screws to accommodate a limited swinging movement of the cam-disk thereon. The sleeves F are splined to the central shaft, A, for the purpose of giving the cam-disk and guide-wheel firm support while the machine is in operation. A limited sliding motion, however, may be imparted to them through the adjusting-rod E, hereinafter described.

Angular studs or arms i and j, Fig. 1, are secured to the cam-disks, and similar arms, h and k, are secured to the disks K. These arms are connected in pairs—h with i and k with j—by links or bars l. The arms and links together form a jointed arm or toggle-joint, which is peculiarly adapted to the alternating motion of the said disks and guide-wheels made necessary by changes in their relative positions, as when a change is required in the stretch or spread to be imparted to the cloth, the joints L in the said arms are the fulcrum-pivots on which the cam-disks and guide-wheels are deflected to increase or decrease the spread of the stretcher-blocks. Their position in the machine is between the guide-wheels and the disks K in the cylinder-heads, closely approaching the guide-wheels, and substantially at the end of a radius thereof. The lugs x, which connect each series of stretcher-blocks to the guide-wheels, will occupy substantially the same plane (parallel to the axis of the cylinder) as the joints L when they are brought opposite thereto by the revolution of the cylinder, provided the said joints are in proper position. This is practically the starting-place for the blocks C, for here the said blocks are drawn together, and the central longitudinal line thereof in that position will lie in the same plane as that passing through the line of nearest approach of the cam-disks and guide-wheels, respectively. Precision should be observed in locating the joints L, in order that the stretcher-blocks C be brought around to and start from the same point, whatever be the angle of the cams and guide-wheels.

The arms h and k, usually attached to the disks at the cylinder-heads, may be fastened to the central shaft, like t, Fig. 5. We prefer, however, to secure them to the disks K, as shown at h and k, Fig. 1. The guide-wheels ordinarily used in machines of this class may be readily adapted to our machine.

In our machine the general construction of the exterior of the cylinder, which consists of

longitudinal rows of stretcher-blocks, the manner of linking such blocks together, the parallel rods extending lengthwise to connect both heads of the cylinder, and upon which the 70 stretcher-blocks travel while the machine is in operation, and the circular rests or cylinder-heads are essentially the same as in all machines of this class. The surface of the machine is made up of rows of serrated blocks or 75 lags C, which are supported by parallel rods a, connecting the heads of the cylinder. An end view of one of such blocks is shown at C, Fig. 6, and a view of two rows is shown in Fig. 1. In Fig. 1 one of these rows is extended at 80 full spread and the other row is shown with all the blocks in close contact with each other. In a completed machine the entire circumference of the cylinder is covered with similar blocks, which have grooves w, Fig. 6, adapted 85 to the parallel rods a, Figs. 1 and 6, on which they are moved by the cams and guide-wheels. One-half of said stretcher-blocks, taken from a line through the short diameter centrally of the machine, are under the control of one cam 90 and guide-wheel, and the balance are under the control of the other cam and guide-wheel. To the outermost block of each row is attached a ball or lug, x, Figs. 1 and 7, extending inwardly therefrom, which fits loosely in the 95 pocket or chamber in the grooved periphery of the guide-wheel B. The stretcher-blocks C are linked together by links y, Figs. 7 and 8, so that motion imparted through the rotation of the guide-wheels to the outside lag or stretcher-block will be communicated to the adjoining block and thence to the next, and so on through the whole series. The machine is adjusted so that the line of divergence of the stretcher-blocks begins near the point where the cloth 100 first comes in contact with the machine, and the divergence thereof increases up to a point a little beyond where the cloth leaves it, which is usually one-half the revolution. From this point during the remainder of the revolution 105 the stretcher-blocks converge. In Fig. 1 the upper row of stretcher-blocks is shown at the maximum stretch and the lower row at the point of nearest approach. It will be seen that the sum of the lengths of the several 110 blocks that make the row is considerably less than the length of the cylinder; but the guide-wheels may be so deflected with the cam-disks as to spread each row successively to embrace 115 the whole space between the cylinder-heads. 120

The angle of divergence of the guide-wheels may be varied at pleasure while the machine is in operation, so as to effect any given stretch within the capacity of the machine. This is accomplished through the adjusting-rod E, extending from end to end of the cylinder parallel with the central shaft, provided with worm and gear d c, Fig. 9, the gear-wheel being secured to one end of the said rod E, which projects through the cylinder-head. The adjusting-rod is provided with two screw-threads inside the cylinder-heads—the one a right and 125 130

the other a left hand screw—and these screws are adapted to and work in corresponding female screws in the projections *g* of the sleeves *F*. Threaded bushings of superior metal may 5 be inserted in the said projections and fastened therein by set-screws *o*, should the screw-threads in the said projections prove inadequate. A hub on the rod *E*, inside the cylinder-head, with the hub attached to the gear-wheel outside, holds the adjusting-rod securely in place. To increase or decrease the stretch or spread upon the cloth, turn the hand-wheel *m* to the right or left, which, communicating motion to the gear *c* through the worm *d*, which 10 is secured to the opposite end of the hand-wheel shaft *n*, Fig. 9, causes the rod *E*, Fig. 1, to act on the sleeves *F* and impart a sliding motion to them on the central shaft. The cam-disks and 15 guide-wheels being secured to the sleeves *F*, and also fastened to the jointed arms, as hereinbefore described, the sliding motion thus imparted will cause the line of deflection of the guide-wheels to be changed, the joints *L* of the jointed arms being the fulcra or pivotal 20 points on which the cam-disks and guide-wheels vibrate when these changes are desired. It will be observed that the change being effected through the rod *E*, communicating with both 25 guide-wheels through the cam-disks, the series of serrated blocks under the control of each 30 guide-wheel will be affected alike—that is, if one series be given more spread the other series will be spread at the same time and to the same extent, and if one series be contracted so 35 will the other series of blocks be correspondingly changed; and herein a precision is attained by this method of adjustment that would be impossible in the ordinary way—namely, by the eye or judgment of the operator. The im- 40 portance of this method of adjustment will be better appreciated when it is understood that a deflection of one of the guide-wheels more than the other causes a greater spread of the 45 stretcher-blocks under its control than those under the control of its fellow guide-wheel, the effect of which would be to cause the cloth to run zigzag over the cylinder to spread it more on one side than the other, and to render it 50 puckered and corrugated.

50 In our improved method of adjustment we can vary the stretch at pleasure while the machine is running at full speed, and both guide-wheels being changed in their angle of divergence simultaneously a simultaneous change 55 proportioned to such variation is produced in both series of stretcher-blocks without delaying the work to make the change.

We are aware that pre-existing machines of this general character may be found on reference

to United States Letters Patent No. 101,811, 60 of 1870, and No. 14,659, of 1856, English Letters Patent No. 1,317 of 1865, No. 7,655, old law, and No. 509 of 1854.

We do not claim the stretcher-blocks *C*, the manner of linking them together, nor the parallel rods *a*, connecting the cylinder-heads on which the stretcher-blocks are moved by the cams and guide-wheels; but 65

What we claim in cloth-spreading machines as our invention, and desire to secure by Letters Patent, is—

1. In combination, substantially as specified, the adjustable cam-disks and guide-wheels, devices for adjustment, substantially as described, and the fixed fulcra for said disks, located substantially at the end of a radius of 75 the guide-wheels.

2. The combination of the cylinder provided with parallel rods, the series of linked stretcher-blocks, the guide-wheels, the cam-disks chambered out to serve as reservoirs for oil, fixed fulcra for said disks situated near their peripheries, and means of adjustment, substantially as described. 80

3. In combination, substantially as specified, 85 the adjustable cam-disks and guide-wheels, the central shaft, the sleeves splined thereto, and the right and left hand screw-threaded rod for simultaneously changing said cam-disks and guide-wheels.

4. The combination, substantially as specified, of the cylinder provided with parallel rods, the series of linked stretcher-blocks, the adjustable cam-disks, and the guide-wheels having fixed fulcra near their peripheries. 90

5. The combination of the adjustable cam-disk and guide-wheel, the cylinder-head, the jointed arm, one end of which is fixed to the said cylinder-head and the other end to the said cam-disk, and suitable means of adjustment, substantially as specified. 95

6. The combination, substantially as specified, of the adjustable cam-disks and guide-wheels, sleeves splined to the central shaft and having projections provided with female 105 screws, and the adjusting-rod provided with a right and left hand screw adapted to the female screws in said projections to simultaneously adjust the cam-disks and guide-wheels to their proper planes of divergence while the 110 machine is at rest or in motion.
